R. L. Ramsey,
INVENTOR

BY Victor J. Evans

ATTORNEY

WITNESS:

P. J. Hickey

UNITED STATES PATENT OFFICE.

ROBERT L. RAMSEY, OF BEN WHEELER, TEXAS.

ORGANIZED LIFTING MECHANISM.

Original application filed February 19, 1925, Serial No. 10,356. Divided and this application filed August 7, 1926. Serial No. 127,956.

My present invention pertains to lifting means, and contemplates the provision of an organized lifting mechanism of peculiar and advantageous construction, designed more especially for use as a lamp support in the hot air incubator constituting the subject of my contemporary application, filed February 19, 1925, Serial No. 10,356, of which this application is a division.

10 In the accompanying drawings, forming part of this application:

Figure 1 is a fragmentary sectional view of an incubator showing the improved lamp supporting means in elevation and associated therewith.

Figure 2 is a similar view showing the lamp construction with its support in section.

Figure 3 is a side elevation of the incubator lamp and supporting means thereof with the lamp flues in section.

Referring to the drawings in detail the letter A indicates an incubator of the type referred to, B the heating flue, C the ventilating flues both of which are disposed in a casing D and which are fully described in my said application, Serial No. 10,356.

Depending from the lower side walls of the flue casing D are guide bars 1 receiving sleeves 2 for the vertical slideable movement of the sleeves thereon. The sleeves are provided with outwardly extending arms 3 having right angled downturned ends 4. Passing through the lower end portions of the guide bars 1 is a rock shaft 5 formed with a handle 6 at one end for rocking the same for a purpose which will be presently apparent, and fixed to said rock shaft at its ends are cams 7 of similar construction and adapted to engage the outwardly extending arms 3 of the sleeves 2 for raising and lowering a platform 8 which carries the lamp fount 9 formed with a filling spout 10, and having secured thereon in spaced parallel relation with respect to each other a pair of burners 11 and 12 with the chimneys 13 and 14 therefor as clearly shown in Figure 3 of the drawings and which are adjustably associated with the flues B and C. The platform 8 is supported in its lowermost position by a cross piece 15 and has provided

on its ends the sleeves 2 as clearly shown in Figure 3 of the drawings.

Manifestly when the cams 7 are positioned as shown in Figures 2 and 3, the chimneys 13 and 14 will be arranged with their upper ends in the lower ends of the flues B and C respectively, while when the swinging handle 6 is manipulated to swing the cams in the direction indicated by the arrow in Figure 1, the platform 8 will be permitted to gravitate until the fount rests on the bar 15 so that access may be readily gained to the fount for filling the same with oil and access may be gained also to the burners for the adjustment of their wicks or the trimming of the wicks or for the removal thereof and the replacement of same with fresh wicks. After any one of the operations above indicated, the platform is readily restored to working position by swinging the cams 7 in the opposite direction through the instrumentality of the handle 6 as will be readily apparent.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

In combination, vertical spaced guide bars in parallelism, a cross bar interposed between and connecting the lower ends of said vertical bars, a vertical movable platform disposed between said guide bars and adapted in one position to be supported by said cross bar, said platform having at its ends vertical sleeves movable on said guide bars, and said sleeves having outwardly and downwardly extending arms, a rock shaft journaled in said vertical guide bars, below said cross bar and having a handle at one end, and vertically-disposed cams fixed to said rock shaft alongside said sleeves and located between the sleeves and the downwardly extending portions of said arms.

In testimony whereof I affix my signature.

ROBERT L. RAMSEY.
